H. C. WILCOX, OF MERIDEN, CONNECTICUT, ASSIGNOR TO MERIDEN BRITANNIA COMPANY, OF THE SAME PLACE.

Design No. 3,429, dated March 23, 1869.

DESIGN FOR A FORK OR SPOON-HANDLE.

The Schedule referred to in these Letters Patent and making part of the same.

To all whom it may concern:

Be it known that I, H. C. WILCOX, of the city of Meriden, county of New Haven, and State of Connecticut, have invented or produced a new and useful Design for a Handle for Knife, Fork, Spoon, &c.; and to enable others skilled in the art to make the same, I will proceed to describe, referring to the drawings, or photographic views, in which the same letters indicate like parts.

In the accompanying illustrations—

a is a handle of a knife, fork, spoon, &c.

b is the upper end.

c is a bead or beads, formed on the edge thereof.

d is a circular enlargement, embellished with an elongated figure, *e*.

f is a configuration upon the upper end thereof.

The whole is combined to produce a new and useful design for a handle for a knife, fork, spoon, &c.

I claim the design for a handle for a knife, fork, spoon, &c., substantially as described.

H. C. WILCOX. [L. S.]
